(57) **CLAIM**

The ornamental design for a storage device, as shown and described.

DESCRIPTION

FIG. 1 is a front right perspective view of a storage device in accordance with the claimed design;

FIG. 2 is a front elevation view of the design of FIG. 1; FIG. 3 is a rear elevation view of the design of FIG. 1; FIG. 4 is a right side elevation view of the design of FIG. 1; FIG. 5 is a left side elevation view of the design of FIG. 1; FIG. 6 is a top plan view of the design of FIG. 1; and, FIG. 7 is a bottom plan view of the design of FIG. 1.

The dash-dash broken lines in the figures depict portions of the storage device that form no part of the claimed design. The dot-dash broken lines in the figures immediately adjacent the shaded surfaces represent a boundary between claimed and unclaimed subject matter and form no part of the claimed design.

The cross-hatched pattern is provided to represent a fabric material.

The labels used herein to describe orientation (e.g., front, top, left, right) are merely for reference and are not intended to limit the interpretation of the design.
